(57) **CLAIM**

The ornamental design for a round funnel top container, as shown and described.

DESCRIPTION

FIG. 1 is a top frontal perspective view of a round funnel top container according to my new design;

FIG. 2 is a front view of the round funnel top container shown in FIG. 1;

FIG. 3 is a back view of the round funnel top container shown in FIG. 1;

FIG. 4 is a right side view of the round funnel top container shown in FIG. 1;

FIG. 5 is a left side view of the round funnel top container shown in FIG. 1;

FIG. 6 is a top view of the round funnel top container shown in FIG. 1; and,

FIG. 7 is a bottom view of the round funnel top container shown in FIG. 1.

The ornamental design which is claimed is shown in solid lines in the drawings. The broken lines in the drawings are for illustrative purposes only and form no part of the claimed design.

1 Claim, 7 Drawing Sheets
